CLAIM

The ornamental design for a scanner as shown and described.

DESCRIPTION

FIG. 1 is a perspective view showing a first embodiment of a scanner design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing a second embodiment of a scanner design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The portions of the scanner shown in broken lines are included for the purpose of illustration unclaimed portions of the scanner and form no part of the claimed design.

1 Claim, 8 Drawing Sheets
